US00D628719S

(12) **United States Design Patent**
Wagner

(10) **Patent No.:** **US D628,719 S**
(45) **Date of Patent:** **** Dec. 7, 2010**

(54) **METAL BAND INLAY FOR TRIM STRIPS OR
SEALING STRIPS**

5,305,552 A * 4/1994 Guillon 49/490.1
D577,445 S * 9/2008 Durrant D25/164

(75) Inventor: **Joachim Wagner**, Neckarwestheim (DE)

* cited by examiner

(73) Assignee: **BFC Buro- und Fahrzeugtechnik
GmbH & Co. Prod. KG**, Remseck
(Aldingen) (DE)

Primary Examiner—Doris Clark
(74) *Attorney, Agent, or Firm*—Gifford, Krass, Sprinkle,
Anderson & Citkowski, P.C.

(**) Term: **14 Years**

(57) **CLAIM**

(21) Appl. No.: **29/323,457**

I claim the ornamental design for metal band inlay for trim
strips or sealing strips, as shown and described.

(22) Filed: **Aug. 26, 2008**

DESCRIPTION

(30) **Foreign Application Priority Data**

Jun. 4, 2008 (EM) 000961529-010

FIG. 1 is a fragmentary perspective view showing my new
design.

(51) **LOC (9) Cl.** **25-01**

FIG. 2 is a fragmentary top plan view thereof.

(52) **U.S. Cl.** **D25/164**

FIG. 3 is an end view thereof, the opposite end is identical.

(58) **Field of Classification Search** D25/164;

428/573, 574, 134; 49/495.1, 500.1, 304,

49/490.1

FIG. 4 is a side view thereof, the opposite side is identical.

See application file for complete search history.

FIG. 5 is a fragmented top plan view of a second embodiment.

(56) **References Cited**

FIG. 6 is a fragmented top plan view of a third embodiment.

U.S. PATENT DOCUMENTS

FIG. 7 is a fragmented top plan view of a fourth embodiment.

5,302,466 A * 4/1994 Davis et al. 428/573

FIG. 8 is a fragmented top plan view of a fifth embodiment.

FIG. 9 is a fragmented top plan view of a sixth embodiment.

FIG. 10 is a fragmented top plan view of a seventh embodiment.

FIG. 11 is a fragmented top plan view of an eighth embodiment.

FIG. 12 is a fragmented top plan view of a ninth embodiment;
and,

FIG. 13 is a fragmented top plan view of a tenth embodiment.

UNITED STATES PATENT AND TRADEMARK OFFICE
CERTIFICATE OF CORRECTION

PATENT NO. : D628,719 S
APPLICATION NO. : 29/323457
DATED : December 7, 2010
INVENTOR(S) : Joachim Wagner

Page 1 of 2

It is certified that error appears in the above-identified patent and that said Letters Patent is hereby corrected as shown below:

Delete the title page showing an illustrative figure, and substitute the attached title page therefor.

Delete sheet 6 of 7 in the drawings.

Signed and Sealed this
First Day of March, 2011

David J. Kappos
Director of the United States Patent and Trademark Office
